WRAPPING MACHINE

Walter Haynes Sergeant, Middletown, N. Y., assignor to Ideal Wrapping Machine Company, Middletown, N. Y., a corporation of New York

Application August 15, 1938, Serial No. 224,932

17 Claims. (Cl. 93—4)

This invention relates to an improved form of wrapping machine particularly adapted for wrapping a number of individually wrapped caramels or other rectangular pieces of candy into a single package. This invention also contemplates the use of Cellophane as a wrapping material and takes advantage of the property of Cellophane of adhering to itself when heated and pressed together in the final sealing of the wrapped package. Although the machine embodying my invention is designed to wrap candies in groups, it may also be used to wrap single candies or other articles besides candies.

Machines have been made, prior to my invention, for wrapping a plurality of candies into a single package, but these machines have required frequent attention from the operator because of jamming caused by variation in the size of the candies. This variation in size causes little trouble with single candies, but when candies are wrapped together in groups, the variations in size of the separate candies add up, and the total often exceeds that which the machine can accommodate. One of the principal objects of my invention is to provide a mechanism for eliminating this variation in the size of the candies and to thus prevent jamming of the machine.

Another object of my invention is to provide an improved and simplified wrapping mechanism having a smaller number of parts than hitherto thought to be necessary.

Another object of my invention is to provide a machine for wrapping candies in which the wrapping material is folded down from all sides onto the ends of the candies in superposed layers, so that the wrapping material can be securely held onto the candy by merely causing the layers of wrapping material at the ends of the candies to adhere to each other.

Another object of my invention is to provide an improved mechanism for feeding candies into a wrapping mechanism in groups so that several candies can be wrapped together.

Still another object of my invention is to provide an improved feeding mechanism especially adapted to carry thin candies on edge without allowing them to fall over.

A further object of this invention is to provide an improved discharge box mounting which will allow the discharge box for receiving candies from the wrapping mechanism to yield freely in case candies get jammed between it and the wrapping mechanism.

With these and other objects in view, which

will become more apparent in the following description and disclosures in the drawings, my invention comprises the novel features of construction and combination hereinafter described and more specifically pointed out in the appended claims.

In the drawings, which illustrate a preferred embodiment of this invention and in which similar reference numerals refer to similar features in the different views:

Figure 1 is a front elevation of the machine with the lower part of the supporting base broken off.

Figure 2 is a top plan view of the machine on an enlarged scale.

Figure 3 is an enlarged plan view of the feeding and sizing mechanism of the machine, a portion of the wrapping wheel being shown in its proper relation and in section.

Figure 4 is a vertical section through a portion of the feeding mechanism taken on the line IV—IV of Figure 2 and looking in the direction of the arrows.

Figure 5 is a horizontal section view taken on the line V—V of Figure 4, looking down in the direction of the arrows.

Figure 6 is a vertical section taken on the line VI—VI of Figure 3 and looking in the direction of the arrows.

Figure 7 is a vertical section taken on the line VII—VII of Figure 3, looking in the direction of the arrows.

Figure 8 is a vertical section taken on the line VIII—VIII of Figure 2 and looking in the direction of the arrows.

Figure 9 is a plan view of the more important driving members of the machine in their proper relative positions.

Figure 10 is a vertical sectional view taken on the line X—X of Figure 9 and looking in the direction of the arrows.

Figure 11 is a plan view of the discharge portion of the machine.

Figure 12 is a vertical section with parts in elevation, taken on the line XII—XII of Figure 11 and looking in the direction of the arrows.

Figure 13 is an end elevation of the discharge portion of the apparatus, looking in the direction of the arrows from the line XIII—XIII of Figure 11.

Figure 14 is a vertical section taken on the line XIV—XIV of Figure 11 and looking in the direction of the arrows.

Figure 15 is a vertical section taken on the

line XV—XV of Figure 11 and looking in the direction of the arrows.

Figures 16 to 22 are isometric views showing the successive steps performed by the machine in wrapping up several pieces of candy into a single package.

The embodiment of the invention shown in the drawings is a machine for taking a predetermined number of small rectangular caramels that have been previously wrapped in another machine and wrapping them up in Cellophane into a single package. In general, the machine comprises a base 21 and an oil case 22 supported by the base and forming the frame of the machine. On one side of the base 21 is mounted a bracket 23 which carries a large roll 24 of Cellophane or other suitable wrapping material. From the roll 24 the strip of Cellophane 25 passes over tensioning rollers 26 and 27 and through a brushing device 28 to the paper feeding mechanism 29. In their construction and operation, these parts are similar to corresponding parts shown in my Patents No. 1,574,120 and No. 2,014,593, and need not be described here in detail.

On the side of the oil case 22 is mounted a 25 feeding and sizing mechanism 31, which will be described in detail below. This mechanism receives the individually wrapped caramels or candies which are fed to the machine, and it forms successive groups of candies, each group having a 30 predetermined number in it. The successive groups of candies are taken one at a time by the feeding and sizing mechanism and pressed together so that they will have the proper size to go through the wrapping mechanism. Each 35 group of candies is then pushed into a pocket 32 in the periphery of a wrapping wheel 33 which is also mounted on the side of the oil case 22.

As the group of candies enters the pocket 32 of the wrapping wheel 33, it carries with it a piece 40 of Cellophane sheared off from the strip of Cellophane 25 by the paper or Cellophane feeding mechanism 29. The wrapping wheel 33, in conjunction with other wrapping mechanism located upon the side of the oil case 22, folds the piece of 45 Cellophane around the pieces of candy, as will be described more in detail below, and then, after the wheel has rotated through an angle of 180°, discharges the wrapped candies into a discharge box 34. As one package after another is fed into 50 the discharge box, each package pushes the ones ahead of it through the box and into a discharge chute 35. The packages have been wrapped so that the Cellophane is folded down from all four sides over the ends of the packages, and they are 55 pushed sideways through the chute so that their ends are exposed. As the packages of candy enter the discharge chute 35, their ends are pressed and ironed by heated shoes 36 so as to make the overlapping folds on the ends of the 60 packages adhere to each other. This operation completes the wrapping of the candies.

Feeding and sizing mechanism

One of the important features of this new machine is the feeding and sizing mechanism 31, which insures that the groups of candies fed into the wrapping wheel 33 are not too large to fit properly into the pocket 32 thereof. The details of this mechanism are shown in Figures 3, 4, 5, 6 and 7. The feeding and sizing mechanism 31 comprises three distinct and interrelated mechanisms: namely, the belt feed mechanism for bringing the candies to the machine, the sizing mechanism for pressing the groups of candies 75

down to a predetermined size to insure that they will fit into the pocket of the wrapping wheel 33, and a feed plunger mechanism for removing the proper number of candies from the feed belt and placing them in the sizing mechanism and subsequently moving them into the pocket 32 of the wrapping wheel 33. The major part of these three mechanisms are supported by a feed belt bracket 37 secured to one side of the oil case 22 as shown in Figures 1, 2 and 8.

The belt feed mechanism, in general, is similar to that shown in my U. S. Letters Patent No. 1,654,146, issued December 27, 1927, and need not be described in great detail. In brief, it includes a pair of feed belt pulleys 38 and 39 fixed to shafts 41 and 42 which are rotatably mounted in the feed belt bracket 37. These two pulleys 38 and 39, in connection with an outboard pulley 43, seen in Figure 1, serve to carry a feed belt 44. The upper reach of the feed belt 44 lies in a groove in the top of a fixed plate or feed plunger bracket 45 secured to the top of the feed belt bracket 37 and serves to bring candies individually wrapped in another machine to this machine to be wrapped up into packages. The inboard feed belt pulleys 38 and 39 are driven through their shafts 41 and 42 and a train of gears 46, 47, 48, 49, 50, 51 and 52 from a Geneva gear 53, which also drives the wrapping wheel 33. Driving the belt 44 from the Geneva gear 53 causes it to move forward intermittently so that it has a period of rest between each forward movement. Thus, the belt 44 comes to rest each time that a group of candies is to be removed from it, and then it moves forward again to bring another group of candies into place.

Since the candies 54 are carried on edge by the belt, as shown in Figure 4, there is a tendency for them, and especially the leading candy, to fall forward when the belt starts or stops. In order to prevent this, I have provided a drag mechanism which exerts a slight retarding force on the upper edges of the candies and prevents their falling forward. This mechanism comprises a belt cover plate 55 which lies directly above the point where the candies 54 are removed from the belt. The cover plate 55 has a large central aperture in which are mounted a large number of small rolls 56 which hang down into the path of the candies 54. These rolls are carried on pins or spindles 57 which extend across the opening in the belt cover plate 55 in a direction transverse to the direction of movement of the belt 44. The ends of the pins 57, as shown in Figure 6, are supported in vertical slots in the belt cover plate 55. This allows the rolls 56 and the pins 57 to rise slightly and allow the candies 54 to pass beneath them, as shown in Figure 4. At the same time, it provides a slight resistance to the forward movement of the upper parts of the candies, which I have found desirable in order to prevent their falling forward.

The sizing mechanism is mounted on the feed plunger bracket 45 alongside of the feed belt 44 and is arranged to act on the groups of candies after they have been removed from the feed belt. This mechanism comprises a sizing plunger 58 mounted in a guide 59 which is bolted or otherwise fixed to the top of the feed plunger bracket 45. A stud having a flange 61 secured by a pair of screws to the upper surface of the sizing plunger 58 and projecting up through a slot in the guide 59 forms a connection by means of which the plunger 58 is reciprocated. The part of the stud below the flange 61 fits into a hole

in the sizing plunger 58, and the portion above the flange 61 forms a bearing for one end of a link 62. The other end of the link 62 is connected to the outer end of an arm 63 fixed to the upper end of a vertical rock shaft 64. The rock shaft 64 is journaled in a bearing 65 carried by the feed plunger bracket 45. The lower end of the rock shaft 64 has an arm 66 keyed to it. The end of the rock shaft arm 66 is connected by a link 67 to a lever 68 fulcrumed within the oil case 22. As shown in Figures 8 and 9, the lever 68 carries a roller 69 which is acted upon by a cam 71 mounted on the main shaft 72 of the machine. The cam 71 is shaped so as to cause the sizing plunger 58 to reciprocate in the correct synchronism with the movements of the other elements of the machine, as described below.

The feed plunger mechanism forms the third part of the feeding and sizing mechanism and is shown in Figures 1, 2, 3, 5 and 6. It comprises a feed plunger 73 having an integral head 74 and reciprocably mounted in a feed plunger slide 75. The slide 75 is carried by the feed plunger bracket 45 and is placed at right angles to the path of the belt 44 and the sizing plunger 58, as shown in Figure 3. The head 74 of the feed plunger 73 is considerably wider than the body of the feed plunger and has a backwardly extending skirt or stop 76 riveted to one side in order to prevent candies from being carried behind it by the belt 44 when it is in its forward position.

The feed plunger 73 is provided with a stud 77 which projects out laterally through a slot in the feed plunger slide 75 and which is connected by a link 78 to a depending lever 79. These connections are shown in Figure 1. The lever 79 is pivoted on a bracket 80 fastened to the oil case 22 and is operated by means of a link 81 from an ejector lever 82. The ejector lever 82 is rotatably mounted upon the hub of an ejector lever retainer 83 which is keyed to a rock shaft 84 extending out from the oil case 22. As seen in Figure 8, the rock shaft 84 is carried in a long outwardly projecting bearing bracket 85 mounted on the side of the oil case 22 and on an inner bearing 86 mounted within the oil case. Keyed to the rock shaft 84 near its inner end is an upwardly extending arm 87 whose upper end is provided with a laterally extending roller 88. The roller 88 travels in a groove 89 in the side of the cam 71, as shown in Figure 10.

The cam groove 89 is shaped so as to bring the lever 87 forward in two steps and to return it to its original position in a single step for a purpose which will presently be described. This movement is transmitted by the rock shaft 84 to the ejector lever retainer 83. The ejector lever 82 is not fixed directly to the ejector lever retainer 83 or to the rock shaft 84 but, as stated above, is journaled upon the hub of the retainer 83. The lever 82 and retainer 83 are normally kept in a fixed relation to each other by means of a spring 90 (shown in Figure 1) which presses the lever against a stop on the retainer. This construction is similar to that shown in my U. S. Letters Patent No. 2,014,593, issued on September 17, 1935, and provides enough resiliency in the drive of the feed plunger 73 to prevent damage in case the machine should accidentally become jammed.

Operation of the feeding and sizing mechanism

The operation of the above-described feeding and sizing mechanism is as follows: The feed belt 44 is kept supplied with individually wrapped

candies 54, either by an operator who places manually upon it the output of several candy-wrapping machines or by some suitable mechanism designed for this purpose. During each 5 cycle of operation of the machine, the feed belt 44 is moved forward a distance equal to or slightly greater than the total thickness of the number of individual candies to be wrapped up in a single package. This brings the candies up 10 against a candy stop 91 extending across the feed belt 44 in line with the far side of the wrapping wheel 33. The desired number of candies is then directly in front of the head 74 of the feed plunger 73. The feed plunger 73 then moves 15 forward in the first step of its forward motion and pushes the desired number of candies off the feed belt 44 and in front of the sizing plunger 58. At this point the feed plunger 73 stops momentarily, due to the shape of the groove 89 in the cam 71. The sizing plunger 58 then moves 20 forward from the full line position shown in Figure 5 to the dotted line position shown in the same figure, in which position the distance between its face and the opposed face of the candy stop 91 is slightly less than the width of the wrapping wheel 33. If the total width of the candies in this space was originally greater than this dimension, the candies are now squeezed 25 down until they will fit readily into the pockets 32 of the wrapping wheel 33. The feed plunger 73 then makes the second step of its forward movement and pushes the candy into a pocket of the wrapping wheel 33, which at this moment is 30 stationary. As the candies are pushed into the pockets 32 of the wrapping wheel, they carry with them the end 25 of the strip of wrapping material or Cellophane, which has been moved up into position between the feeding and sizing mechanism and the wrapping wheel by means of the paper feeding mechanism 29. The paper feeding mechanism 29 is synchronized so that it 35 shears off the correct size or length of wrapping material or Cellophane from the end of the strip 25 as soon as the end begins to be held by the 40 candies entering the wrapping wheel pocket 32. Thus, it cooperates with the feeding and sizing mechanism to place in the wrapping wheel pockets 32 the proper number of pieces of candy and 45 the proper size piece of wrapping material or Cellophane.

Wrapping mechanism

The wrapping wheel 33 is of the general type shown in U. S. Letters Patent No. 1,082,463, issued to A. E. Hopkins and O. S. Fellows on December 23, 1913, and in my Patent No. 2,014,593, issued September 17, 1935. The wrapping wheel 33 is provided with six pockets 32 extending across its periphery and spaced evenly around it. As 55 shown in Figures 3 and 6, each pocket 32 of the wrapping wheel is provided with a pair of springs 102, one at each side of the pocket, by means of which candies are resiliently retained in the pocket. In the bottom of each pocket is mounted 60 a plunger 103 which can slide in and out and by means of which the candies are ejected from the wrapping wheel at the end of the wrapping operation. Each end of each pocket is partly closed off by an end finger or plate 104 secured to the 65 side of the wrapping wheel. As will be seen from Figure 6, the end finger 104 is narrower than the pocket 32 so that slots are left at each side of the finger 104 at the corners of the pocket.

By providing the wrapping wheel pockets 32 with end fingers 104 as described above, the first

four folds in the sheet of wrapping material 25 will be made as the pieces of candy 54 are placed in the wrapping wheel pocket. As the candies 54 are about to enter the wrapping wheel pocket 32, their position relative to the sheet of wrapping material 25 is as shown in Figure 16. As the candies are pushed into the pocket, the springs 102 at each side of the pocket form the two side folds 105 and 106, and the end fingers 104 form the first end folds 107.

The formation of the upper side fold 106 is assisted by a pair of paper break arms 110, one of which can be seen in Figure 1 on the near side of the wrapping wheel 33. The two paper break arms 110 are arranged symmetrically at the two sides of the wrapping wheel 33 and swing down and forward, just before the candies are loaded into the pocket 32, to a position in which they are in line with the upper side of the pocket 32. In this position, they form, in effect, continuations of the pocket spring 102 forming the upper side of the pocket, so that the end portions of the side fold 106 that project beyond the pocket and form the end folds 109 are folded down by the paper break arms 110 in much the same way as the main part of the side fold 106 is folded down by the pocket spring 102. The result is as shown in Figure 17. At the same time the second and third end folds 108 and 109 are partly formed and project out through the slots lying at each side of the end fingers 104.

After a group of candies is placed in the wrapping wheel pocket 32, the wrapping wheel 33 is rotated through one-sixth of a turn so as to bring another pocket 32 into position to be filled and so as to carry the candies in the already filled pocket to position where the remainder of the wrapping mechanism may operate upon them. The rotation of the wrapping wheel 33 takes place step by step, each step being 60°, since the wrapping wheel has six pockets equally spaced around its periphery. The mechanism for accomplishing this step-by-step rotation is similar to that shown in U. S. Patents No. 1,082,463 and No. 2,014,593 mentioned above. This mechanism comprises the Geneva gear 53 already mentioned and an arbor 93 which carries both the Geneva gear and the wrapping wheel 33, as shown in Figure 8. The Geneva gear 53 is rotated step by step by means of pins or rollers 94 carried upon the side of the Geneva gear driver 95. The periphery of the Geneva gear driver 95 is formed into a spur gear which engages with a pinion 96 upon the main shaft 72 of the machine. The Geneva gear driver 95 is provided with two pins 94, placed 180° apart, and has twice the number of gear teeth as the pinion 96. It will therefore cause the Geneva gear 53 to rotate one step for each complete revolution of the main shaft 72. Thus, as the main shaft 72 is rotated, the machine will go through one cycle of operation for each revolution of the shaft 72. As may be noted in Figures 8 and 9, the Geneva gear 53 not only drives the wrapping wheel 33 and the train of gears starting with the gear 52 leading to the belt feed, but also drives another gear 99. This gear is the first of a train of gears leading to the paper feeding mechanism 29 and thus provides the paper feeding mechanism with an intermittent motion so that the paper or Cellophane will be stationary at the time that the candies are being fed into the wrapping wheel 33 and the end of the strip of paper or Cellophane is being cut off. This arrangement is similar to that described in the above-mentioned patents and therefore need not be described herein in greater detail.

The first top fold is made after the wrapping wheel 33 rotates one-sixth of a turn from the position which it occupied when it received the candies from the feeding and sizing mechanism. 5 This fold is made by a roller 111 carried by a finger 112 which is pivoted to the end of a swinging lever 113, shown in Figure 1. The lever 113 is swung or rocked by a link 114 which connects it to an arm 115 on a rock shaft 116. The roller 111 is urged toward the wrapping wheel 33 by means of a coil spring acting between the finger 112 and the lever 113, and a stop is provided to prevent the finger 112 from swinging down too far. Thus, as the arm 113 swings forward, the 10 roller 111 will roll with an even pressure upon the top of the candies and form the first top fold 117 as shown in Figure 18. In order to further insure smooth operation of the machine and to prevent possible breakage of parts in case of accidental damage, the link 114 through which the first top fold mechanism is actuated is provided with a yieldable portion or slide 118 held in its normal position by a coil spring 119. Thus, if the roller 111 should meet any unusual resistance, the spring 119 will yield and prevent any breakage of parts.

The second top fold 121 is made by the movement of the wrapping wheel pocket 32 under a second top fold shoe 122, which is in frictional contact with the top of the wrapping wheel 33. The shoe 122 is held in this position by means of a link 123 and a coil spring 124 acting on the link and pressing it down. As the wrapping wheel 33 rotates through the second 60° from the position in which the candies were loaded into the wrapping wheel pocket 32, the shoe 122 strikes the upstanding edge of the sheet of wrapping material projecting from the wrapping wheel pocket 32 and folds it down into the position shown in Figure 19 at 121.

The second end folds are formed by a pair of swinging end fold shoes 125 mounted upon a shaft 126 above the wrapping wheel 33. The second end fold shoes 125 are actuated through a yieldable link 127 from an arm 128 fixed to the rock shaft 116. The end fold shoes 125 are L-shaped, as shown in Figure 1, and are positioned so that, when they are swung down, their angular ends will swing below the periphery of the wrapping wheel 33 so as not to disturb the projecting ends of the top folds 117 and 121. The end fold shoes 125 therefore engage only the end folds 108 which extend out through the slots at the sides of the fingers 104 at the ends of the wrapping wheel pocket 32. This bends the end folds 108 down into the position shown in Figure 20, in which position they overlie the end fingers 104 on the wrapping wheel.

The third end folds 109, which were partially formed as the candies were loaded into the wrapping wheel pocket 32, are completed by means of a pair of end fold shoes 131 which are held against the opposite sides of the wrapping wheel by means of a pair of resiliently pressed links 132. As the wrapping wheel 33 moves through the third arc of 60° from the position in which the candies were loaded into the pocket 32 to the position in which the candies are discharged, the end folds 109 which project out through the slots at the side of the end fingers 104 strike the edges of the stationary end fold shoes 131 and are folded down into the position shown in Figure 21. This practically completes the wrapping operation.

The final fold in the wrapping of the candies 75 is made as the candies are discharged from the

wrapping wheel 33 into the discharge box 34. As the candies are about to be discharged, they are in the position shown at the extreme right of Figure 11. The transference of the almost completely wrapped candies from the wrapping wheel 33 to the discharge box 34 is accomplished by means of a discharge tappet 133 mounted upon the end of the discharge lever retainer 83. As was pointed out above, the retainer 83 is fixed to the rock shaft 85, which is rocked back and forth by the arm 81 and the groove 89 in the cam 71 within the oil case 22. As the retainer 83 swings forward, the ejector tappet 133 carried by it comes into contact with the wrapping wheel pocket plunger 103 and pushes the plunger outward towards the periphery of the wheel. This causes the head 134 of the plunger to move up from the bottom of the pocket like a piston and to push the candies 54 into the discharge box 34. As the candies enter the discharge box, the projecting end folds 135 are folded down against the ends of the candies on top of the other end folds as shown in Figure 22. This completes the folding of the Cellophane wrapper around the candies and leaves only one more operation to be performed. This operation, the causing of the various layers of Cellophane at the end of the package to stick to each other so that the candies will not become unwrapped, is performed in the discharge chute.

Discharge box and chute

The discharge box 34 is carried by a resilient mounting and is constructed in a manner somewhat similar to that shown in my U. S. Letters Patent No. 1,584,814, issued on May 18, 1926. The mounting comprises a bracket 131 bolted to the side of the oil case 22 and having a vertical link 138 secured to it by a pivot 139. The upper end of the link 138 carries a second pivot 141 which secures it to the bottom 142 of the discharge box. The bottom member 142 is provided with a rearwardly extending horizontal slot 143 which engages a guide key 144 of the bracket 131 and thus forms a slidably connection. This slidable connection and the connection formed by the link 138 serve to allow the discharge box to move backwards a slight distance while maintaining it in proper alignment. The discharge box 34 is pressed towards the wrapping wheel 33 by means of a relief spring 145 acting between a plate 149 fixed to the bracket 131 and the link 138. The discharge box 34 is kept from being moved by the spring 145 beyond its proper position by means of a rod 146 pivoted to the link 138 and having stop nuts 147 which bear against the side of the fixed plate 149 through which the rod 146 passes. This arrangement allows the discharge box 34 to yield in case candies get jammed between it and the wrapping wheel 33 and prevents breakage of parts which might otherwise occur. In case jamming does occur, the discharge box can be moved back easily against the tension of the spring 145 by grasping the depending end of the link 138 and using it as a lever to force the box back.

The discharge box 34 comprises two main members: a bottom 142, already mentioned, and a top member 148 bolted to the bottom 142 and forming with it a passage through which the wrapped candies 54 may pass. In order to hold the packages of candies as they are pushed into the discharge box 34, all four sides of the mouth 75

or opening of the box are made so that they resiliently press upon the packages of candies. The bottom of the box is provided with a hinged lip 152 fixed to a transversely extending shaft 153. Each end of the shaft 153 is provided with a spring coiled around it and fixed to the end of the shaft and to the discharge box. The springs 154 are tensioned so that they tend to rotate the lip 152 upward and press it against the entering package of candies or, if no candies are present, against the bottom of the discharge box member 148.

The sides of the mouth of the discharge box are formed by a pair of laterally slidable side plates 155. The side plates 155 are provided with studs 156 which slide through holes in the depending sides of the upper portion 148 of the discharge box and thus act as guides. Springs 157 on the studs 156, between the side plates 155 and the depending sides of the member 148, serve to press the side plates 155 towards each other and upon the ends of the packages of candies lying between them. The studs 156 on the side plates 155 are provided with nuts 158 which bear against the outside of the discharge box and prevent the side plates 155 from moving in beyond their normal position.

The top of the mouth of the discharge box 34 is formed by a finger or lip 161 mounted upon a pivot 162 in the discharge box top 148. It is pressed down by a spring 163 and prevented from moving beyond its normal position by a stop block 164, as shown in Figure 12.

As the successive packages of candies 54 are pushed into the discharge box 34 from the wrapping wheel 33, each package pushes the previous packages ahead of it through the box. In their passage through the box 34, the candies are supported by a bottom plate 165 whose forward edge is secured to the bottom member 142 of the discharge box and whose rear portion rests in a shallow recess in the top of the discharge box bracket 131.

As the packages of candies 54 leave the discharge box 34, they enter the discharge chute 34, the first portion of which contains the means for ironing the ends of the packages and causing the overlapping end folds of Cellophane to adhere to each other. This portion of the discharge chute comprises a bottom 171 connected to the plate 149 on the back of the discharge box bracket 131 by means of a hinge member 172. The sides are formed by means of a pair of heated shoes or irons 36 pivoted to arms 174 extending out from under the bottom member 171. The portions of the shoes or irons 36 which lie on the side of the path of the candies are resiliently urged towards each other by means of springs 175 acting between the bottom member 171 and downwardly projecting portions of the shoes 36. The springs 175 are prevented from moving the shoes or irons 36 too far by means of stop nuts 176 on a stud 177 fixed to the discharge chute's bottom member 171. The shoes or irons 36 are provided with longitudinally extending cylindrical cavities in which are placed electrical heating elements 178. Current is supplied to the heating elements 178 through a cable 179, and the quantity of current is controlled by means of a rheostat 181 mounted on the top of the oil case 22. This provides a convenient means of controlling the temperature of the shoes 36 so that they will be hot enough to cause the overlapping folds of Cellophane on the ends of the packages of candies to adhere

to each other but will not be hot enough to injuriously affect the candies within the packages.

After the packages of candies pass from between the heated shoes 36, they pass into a sheet metal portion 183 of the discharge chute. This carries the completely wrapped packages away from the machine, and they may leave, as desired, either to other machines or to operators for placing the packages in boxes for shipment.

From the above description it will be seen that I have provided a machine for wrapping and sealing packages of candy which is completely automatic in its operation and which is capable of operating at a high rate of speed. It will also be seen that I have provided a wrapping mechanism which is relatively simple in its construction and operation and which can be manufactured at a lower cost than those produced hitherto. While I have described this machine as being intended for wrapping several pieces of previously wrapped candy into a single package, it will be obvious to those skilled in the art that this machine is suitable for wrapping up individual pieces of candy or other plastic articles besides candy, the machine being used either exactly as it is shown or with slight modifications. It should be understood, therefore, that in the following claims the term "candy" may be either a single piece of candy or several pieces of candy being handled as a group, and vice versa. It is also to be understood that the term "candy" is used in the claims as an example of what the machine may wrap but that the invention includes machines used to wrap any other articles that can be handled in the same manner as candy. It is also to be understood that the invention is not limited to the machine as a whole, but that the separate parts of it are also inventions in their own right, all as defined in the accompanying claims. In addition, it is obvious that details of construction may be varied. I therefore do not purpose limiting this application for patent to the specific details shown or described or otherwise than necessitated by the prior art.

I claim as my invention:

1. In a machine of the class described, a conveyor, means for moving candy from the conveyor to a sizing position, means for squeezing candy in the sizing position down to a predetermined dimension, wrapping mechanism, and means for moving the candy from the sizing position to the wrapping mechanism.

2. In a machine of the class described, a wrapping mechanism, means for conveying preformed pieces of candy to the wrapping mechanism and transferring them thereto, and means operative on the preformed pieces of candy for squeezing the candy to a predetermined dimension before it is transferred to the wrapping mechanism.

3. In a machine of the class described, a feed plunger, a collecting station in the path of the feed plunger, a sizing station beside the collecting station and also in the path of the feed plunger, a candy-wrapping mechanism placed to receive candy at the end of the path of the feed plunger, means for moving said plunger past said collecting and sizing stations to said wrapping mechanism with a momentary hesitation between said collecting and sizing stations, and means operative during said hesitation for squeezing to a predetermined dimension candy carried to said sizing station by said plunger.

4. In a machine for wrapping a stack of candies into a single package, the combination of a wrapping mechanism and mechanism for squeezing

the stack of candies down to a predetermined size to fit into the wrapping mechanism and for loading the stack of candies into the wrapping mechanism.

5. In a machine for wrapping a predetermined number of pieces of candy into a single package, the combination of a wrapping mechanism, mechanism for squeezing the predetermined number of pieces down to a predetermined size so that they will fit into the wrapping mechanism, and means for selecting the predetermined number of pieces from a larger number and moving them in a group to the squeezing mechanism and then to the wrapping mechanism.

10 15. 6. In a machine for wrapping candy, a wrapping mechanism including pockets for receiving the candy and having two sides and two ends, a passage for guiding the candy into the pockets and having a movable wall, means for moving candy through the passage to the pockets of the wrapping mechanism, and means for moving the movable wall of the passage to a position in which the size of the passage is the same as the size of the pocket while the candy is in the passage.

20 25. 7. In a machine for wrapping articles, a pocket having a bottom and two sides and two ends, the ends being formed by thin stiff walls spaced from the sides of the pocket, mechanism for inserting an article to be wrapped into said pocket with a sheet of paper between said article and the bottom and sides and ends of said pocket and with folds of said sheet projecting out from between said sides and said ends and with the ends of said sheet projecting up from between said article and the sides of said pocket, means for folding said ends of said sheet down on top of said article, means for folding said projecting folds in over said thin end plates, and means for ejecting said article out of the top of said pocket.

30 35. 8. In a machine for wrapping articles, the combination of a pocket having a bottom and two sides and two ends, said ends being formed by thin stiff end walls spaced from said sides and projecting up from said bottom a distance less than the height of said articles, means for placing an article in said pocket with a piece of paper having the central portion thereof lying between said article and said bottom and having the end and side portions thereof extending up between said article and said sides and ends and having folds projecting out at the corners of said pocket, and means for bending said folds against said end walls.

40 45. 9. In a machine of the class described, a wrapping wheel having pockets extending across its face and thin end plates extending radially at each end of each pocket, each pocket having a bottom, and the end plates being narrower than the pockets so as to leave slots at the corners of the pockets, mechanism for inserting articles to be wrapped into said pockets with sheets of paper between said articles and the bottom and sides and ends of said pockets and with folds of said sheets projecting through said slots and the ends of said sheets projecting up from between said articles and the sides of said pockets, means for folding said ends of said sheets down on top of said articles, and means for folding said projecting folds in over said thin end plates.

50 55. 10. In a machine of the class described, a wrapping wheel having pockets extending across its face, thin end plates fixed to the wrapping wheel and extending radially at each end of each pocket, the end plates being narrower than the

pockets so as to leave slots at the corners of the pockets, mechanism for rotating the wrapping wheel so that each pocket successively occupies a loading station and two folding stations and a discharging station, mechanism for loading articles into the pockets at the loading station with sheets of paper between the articles and the bottom and sides and ends of the pockets, the sheets of paper at the loading station projecting up from the sides of the pockets and having folds projecting through the slots at the corners of the pockets, means between the loading station and the second folding station for folding down onto the articles the portions of the sheets projecting up from the sides of the pockets, a shaft near the second folding station and parallel to the axis of the wrapping wheel, two L-shaped shoes fixed together and pivoted on said shaft, and means for rocking said shoes on said shaft so that they will fold down over the end plates two of the folds projecting out through the slots at the corners of the pockets.

11. In a wrapping machine having a wrapping wheel with article-receiving pockets extending across its face, an end fold mechanism comprising a shaft having a fixed axis parallel to the axis of the wheel and spaced radially beyond the periphery thereof, a pair of L-shaped folding shoes fixed to each other and rotatable on said shaft, and means to rock the shoes on the shaft so that one shoe swings down at each side of the wheel.

12. In a wrapping machine having a pocket for receiving an article to be wrapped with a piece of wrapping material lying between said article and the sides and bottom of the pocket and projecting up at the sides of said article, a mechanism for folding down one of the upwardly projecting portions of the wrapping material comprising an arm, a freely rotatable roller resiliently mounted on the arm about a fixed axis, and means for swinging the arm so that the roller rolls past the side of the pocket onto said article and folds down the piece of wrapping material.

13. In a wrapping machine having a wrapping wheel and means for discharging articles from the wrapping wheel, a discharge box for receiving articles from the wrapping wheel, a bracket on the machine, a link connected to the bracket and to the discharge box by pivots whose axes lie in a plane perpendicular to the direction in 50

which said articles are discharged from the wrapping wheel, means for preventing rotation of the discharge box, means for resiliently urging the discharge box toward the wrapping wheel, and stop means for limiting movement of the discharge box toward the wrapping wheel.

14. In a wrapping machine, a discharge chute having a bottom member over which articles are adapted to be moved, a pair of side members pivoted to the bottom member at points spaced a substantial distance below the path of said articles and extending along the sides of said path, spring means for swinging the upper parts of said side members towards each other, and means for heating said side members.

15. The method of preparing candies for being wrapped up together in groups which comprises taking a predetermined number of candies, forming them into a row with the candies therein lying flat against each other and isolated from other candies, and subjecting the row of candies to endwise pressure until it is squeezed down to a predetermined dimension.

16. The method of preparing candies for being wrapped up together in groups which comprises taking a predetermined number of candies, forming them into a row with the candies therein lying flat against each other and isolated from other candies, and subjecting the row of candies to endwise pressure while confining the candies against expansion in opposed directions at right angles to the directions of applied pressure until the row is squeezed down to a predetermined dimension.

17. In a wrapping machine having a wrapping wheel with article-receiving pockets extending across the face thereof, and end fold mechanism comprising a shaft parallel to the axis of said wheel and spaced radially a fixed distance beyond the periphery thereof, and a pair of folding shoes swingable on said shaft, each of said shoes having a projecting operative end with a radially extending leading edge so located with respect to said shaft as to swing from a position entirely beyond the periphery of said wheel to a position beside said wheel and entirely within the periphery thereof and thence at least partly across one end of one of said pockets.

WALTER HAYNES SERGENT.
